UNITED STATES PATENT OFFICE

MARY CATHERINE HURLEY, OF DORCHESTER, MASSACHUSETTS

DESIGN FOR A HOLY WATER FONT

Application filed March 23, 1931. Serial No. 39,199. Term of patent 14 years.

To all whom it may concern:

Be it known that I, MARY CATHERINE HURLEY, a citizen of the United States, residing at Dorchester, in the county of Suffolk and State of Massachusetts, have invented a new, original, and ornamental Design for Holy Water Font, of which the following is a specification, reference being had to the accompanying drawings forming part thereof.

In the drawings, Figure 1 is a view in front elevation of a holy water font showing my new design. Figure 2 is a top plan view of the same.

I claim:

The ornamental design for a holy water font as shown.

MARY CATHERINE HURLEY.
